UNITED STATES PATENT OFFICE

141,038

DESIGN FOR A FOB PIN WATCH

Herman Strauss, New York, N. Y.

Application February 9, 1945, Serial No. 117,848

Term of patent 7 years

(Cl. D42—8)

To all whom it may concern:

Be it known that I, Herman Strauss, a citizen of no country, residing at New York city, in the county of New York and State of New York, have invented a new, original, and ornamental Design for a Fob Pin Watch, of which the following is a specification, reference being had to the accompanying drawing, forming part thereof.

In the drawing

Fig. 1 is a perspective view of a fob pin watch, showing my new design;

Fig. 2 is a top plan view.

I claim:

The ornamental design for a fob pin watch, substantially as shown.

HERMAN STRAUSS.
